UNITED STATES PATENT OFFICE.

ALEXIS D. IRVING, OF LOS ANGELES, CALIFORNIA.

COMBINED TELEPHONE-BOOK SUPPORT AND NOTE-PAPER-SUPPLY DEVICE.

SPECIFICATION forming part of Letters Patent No. 749,141, dated January 5, 1904.

Application filed April 29, 1903. Serial No. 154,855. (No model.)

To all whom it may concern:

Be it known that I, ALEXIS D. IRVING, a citizen of the United States, residing at Los Angeles, in the county of Los Angeles, State of California, have invented and discovered a new and useful Combined Telephone-Book Support and Note-Paper-Supply Device; and I do hereby declare the following to be a full, clear, and exact description of the invention, such as will enable others skilled in the art to which it appertains to make and use the same.

This invention relates to a combined telephone-book support and memoranda-paper-supply device adapted for the convenience of persons who are constantly attending to the affairs of railroad-offices, of hotels, and the like, as well as offices where individual business is conducted and frequent telephone messages are received and forwarded.

The invention consists of the combination and arrangement of parts as shown upon the drawings hereto attached, described in the specification, and particularly set forth in the claims.

The purposes and objects of my invention are attained by the combination and arrangement of the parts of the device, as illustrated in the accompanying drawings, in which—

Figure 1 is a perspective view of the receptacle and supporting devices therefor, a portion of one side of the receptacle broken away, showing parts of the paper-supplying devices within the receptacle and a portion of the paper unwound from the roll and protruding through the slot in the said side piece and resting thereon ready for use and a portion of the opposite side piece illustrated partly, the book-supporting devices and a portion of the telephone-book resting thereon. Fig. 2 is a cross-sectional view of my improvement ready for use, the supporting and limited revolving devices removed. Fig. 3 is a view in elevation of one side of my improvement, showing the telephone-book clamped to one side of the receptacle and the limited revolving devices also in elevation and portions of the supporting devices broken away; and Fig. 4 is a detail view.

Similar reference letters and numerals refer to like parts throughout the several views.

The reference-numeral 1 denotes the mov-

able side piece of the receptacle A; 2, the other fixed side piece; 3 3, the two end pieces of the receptacle; and 4 the bottom piece of the receptacle. The side piece 2 of the receptacle is provided with an inturned bracket-lip 5. The said side piece 2 is preferably made of tin, sheet-iron, or other suitable material, and the said bracket-lip is made integral with the side piece 2 and projects into the receptacle and provided with a groove 6, formed by bending the bracket-lip slightly upon itself. Within this groove 6 the yoke 7 of the roll 8 of the note or memoranda paper is retained, and by means of the grooved bracket-lip and the yoke the paper-roll is suspended inside of the receptacle and is ready for use by drawing the free end of the paper 25 through the slot 26 upon the movable side piece 1 and under the keeper 24, secured thereto, as hereinafter more particularly referred to.

The side piece 2 of the receptacle A has two supports 9 9, preferably cast or cut out of and made a part of the said piece 2. One of them projects above and the other below the edge of the piece 2. Each has a horizontally-projecting extension 10. Through these extensions 10 10 perforations 12 12 are made therein, and by means of these two perforations the rod 13 is securely held in place, which clamps the telephone-book to the side piece 2 of the receptacle.

The movable side piece 1 of the receptacle is provided with a slot 26 about the central portion thereof and slightly longer than the width of the strip of memoranda-paper 25 adapted to be drawn therethrough unwound from the roll 8 within the receptacle, as required for use. The movable side piece 1 is hinged to the upper edge of the fixed side piece 2 of the receptacle, and within the enclosure formed by the two side pieces 1 and 2 and the two triangular end pieces 3 3 rolls of memoranda-paper are kept ready for use when required.

The yoke 7 is made by bending a piece of wire of the required length upon itself, leaving the two inwardly-projecting ends 19 19 to be inserted within the central perforation 21 of the roll 8 made therein when the rolls are formed.

A keeper 24 is made of wire or other suitable material. The wire is preferably bent

at each end, as shown upon the drawings, and is secured in the lower edge of the movable side piece 1 of the receptacle and is designed to clamp that portion of memoranda paper 25 which has been drawn through the slot 26 and rests upon the outer face of the movable piece 1 under the keeper 24. By means of the keeper 24 when a memorandum has been finished containing a message it is accurately and quickly separated from the remaining portion of the slip 25 by drawing tightly and diagonally the free end of the slip of paper against the lower edge of the keeper.

The wall-plate 30 of the supporting-bracket 15 for the receptacle is made preferably of a single piece of metal or other suitable material provided with holes therein for nails, screws, or other suitable devices for securing the said plate to the wall of a room, to the end 20 of a desk, or other piece of furniture. The long hollow arm 31 of the bracket is pivotally or otherwise secured to the plate 30, and the outer or free end of the said long arm is bent upwardly, as shown at 32 upon Fig. 1 of the 25 drawings, and is provided with ratchet-teeth 33 upon the upper edge thereof. The short arm 35 projects downwardly and centrally from the under face of the bottom piece 4 of the receptacle, and the said short arm 35 is secured to the bottom piece 4 of the receptacle 30 by means of solder, screws, or any other suitable devices. Upon the downward-projecting edge of the short arm 35 ratchet-teeth 34 are provided, which mesh with the ratchet-teeth 33 upon the upwardly-projecting portion 32 of the bracket-arm 31. The tenon 37 projects downwardly and through the short arm 35, secured to the bottom of the receptacle, and is adapted to be inserted into the up- 40 turned portion 32 of the bracket-arm 31 and extends downwardly and into the portion 32 of the bracket-arm until the ratchet-teeth 33 thereon come in contact with the ratchet-teeth 34 upon the short arm 35, secured to the bottom 45 of the receptacle.

By permitting the receptacle to revolve in one direction only the hand of the operator resting upon the movable side piece 1 of the receptacle and the receiver of the telephone 50 in the other hand the operator can readily record upon the memoranda-paper 25 the message of the person speaking in the opposite end of the telephone.

The advantages of my improvement will 55 readily appear. The convenience afforded by the construction and arrangement of the parts of my improvement is manifest, in that with one hand the person holds the receiver of the telephone and with the other hand conveniently inscribes the message upon the slip of paper 25, which he has drawn through the slot 26 and rests upon the movable side piece 1, while the two ratchets prevent the receptacle A from revolving in the direction in 60 which the hand of the operator presses. Should the message be long, the receiver of the message draws the requisite amount of

paper through the slot 26 of the side piece 1 and under the keeper 24, attached thereto, until the entire message is recorded and the 70 memorandum filled, when by means of the keeper the paper containing the message or memorandum is quickly severed from that portion of the paper upon the outer face of the movable side piece of the receptacle. The 75 space 39 directly above the slot 26, through which the paper slip travels, is set apart for telephone-numbers frequently called for by the owner of the receptacle. The two spaces 40 on the ends of the movable side piece 1 80 are designed for advertising purposes. The two outer faces of the end pieces 3 3 are also intended for advertisements, which bring an income to the owner of my improved device.

The operation of this invention will be 85 readily understood from the foregoing description, taken in connection with the drawings hereto appended.

I do not desire to confine this invention to the specific construction, combination, and 90 arrangement of parts herein shown and described, and the right is reserved to make all changes in and modifications of the same as come within the spirit of this invention; but I do desire to secure as my invention all features of construction and equivalents thereof that come within the scope of my improvement, as herein shown and described, and illustrated upon the drawings appended hereto.

Having described my invention, what I do claim, and desire to secure by Letters Patent, is—

1. A combined telephone-book support and memoranda-paper-supplying device comprising a receptacle, means for revolving the receptacle in one direction, said receptacle comprising sides and end pieces, one side piece fixed and the other movable, the movable side piece being inclined, the said movable side of the receptacle having a slot therein through which memoranda-paper is adapted to be drawn, a paper-supplying device, a keeper secured upon the lower edge of said movable inclined side piece adapted to press 115 the slip of memoranda-paper against said inclined side piece of the receptacle and affording means whereby the receiver of telephone messages can readily separate portions of the paper from the remaining unused portion 120 thereof.

2. A combined telephone-book support and memoranda-paper-supplying device comprising a receptacle containing a paper-supplying device, one side of the receptacle provided 125 with brackets, one projecting above the upper edge and the other projecting below the lower edge of the said side piece of the receptacle, the movable side piece having a slot in the central portion thereof through which the 130 memoranda-paper is adapted to be drawn and means for pressing the slip of memoranda-paper against the movable side piece and affording the operator ready facilities for sev-

ering fragments of the paper containing messages from the remaining portions thereof.

3. A combined telephone-book support and memoranda-paper-supplying device comprising a receptacle, a memoranda-paper-supplying device, the fixed side piece of the receptacle provided with an inturned projecting bracket-lip, said lip having a groove formed therein for the suspending device of the paper-supply, brackets made integral with the fixed side piece, one projecting above the upper edge and the other projecting below the lower edge thereof, said brackets having extensions provided with perforations therein and means for clamping the telephone-book against the fixed side piece of the receptacle in combination with devices whereby the said receptacle revolves only in one direction.

4. A combined book-support and memoranda-paper-supplying device comprising a

receptacle having a book-support upon one side thereof, the opposite side of the receptacle forming a tablet for memoranda-paper and a rest for the hand of a telephone operator, said receptacle provided with a ratchet secured to the under surface of the bottom thereof, a projecting pin or tenon, secured within the ratchet, a hollow bracket-arm having a ratchet secured thereon adapted to mesh with the ratchet secured to the bottom of the receptacle whereby the receptacle is prevented from revolving while the message or memoranda is being recorded.

In testimony whereof I have signed my name to this specification in the presence of two subscribing witnesses.

ALEXIS D. IRVING.
